UNITED STATES PATENT OFFICE.

WILTON D. JACKSON, OF PHILADELPHIA, PENNSYLVANIA, ASSIGNOR TO
FRANK DUTCHER, OF VERSAILLES, PENNSYLVANIA.

TRACK-TORPEDO.

No. 824,019.

Specification of Letters Patent.

Patented June 19, 1906.

Application filed December 26, 1903. Serial No. 186,724.

To all whom it may concern.

Be it known that I, WILTON D. JACKSON, a citizen of the United States, residing in Philadelphia, Pennsylvania, have invented certain Improvements in Track-Torpedoes, of which the following is a specification.

My invention relates to track-torpedoes which are designed to be mounted upon railway or trolley tracks to serve as signals for approaching trains or cars. The object of my invention is to provide an efficient torpedo that may be readily mounted in place, that will act under all conditions, and being constructed of non-metallic material will be absolutely harmless when exploding.

My invention is fully shown in the accompanying drawings, in which—

Figure 1 is a perspective view in full size of my improved track-torpedo. Fig. 2 is a central cross-sectional view of Fig. 3. Fig. 3 is a longitudinal side elevation, partly in section and drawn to the same scale as Fig. 2. Fig. 4 is a view showing a section of rail with the torpedo mounted in operative position with relation thereto.

The object of my invention is to provide a harmless track-torpedo designed to serve as a signal in railroading. As heretofore constructed, track-torpedoes have usually been made of metal and accidents have very frequently happened due to the flight of portion of the metal during or succeeding the explosion of the torpedo.

The object of my invention is to increase the efficiency of a torpedo of this character and at the same time render it absolutely harmless. The torpedo made in accordance with my invention consists of a tube 1, which may be of paper, fabric, papier-mâché, wood, or other similar substance suitably prepared, and in the present instance I prefer to use waterproof paper. Within this waterproof tube is carried the detonating material 2, which may be any suitable substance that will explode under pressure, and to secure this material in place I provide plugs 3 for the ends of the tube, which plugs may be of wood, the material of which the tube is composed, or of any suitable friable substance. The tube is preferably varnished and the plugs are also varnished so as to insure a waterproof condition and render the torpedo

available for use in all kinds of weather. The torpedo is held to the rail by means of a strip of flexible material, such as lead, (indicated at '4 in the accompanying drawings,) and while the lead may be held in place in several different ways I prefer to provide a secondary or supplementary tube 5, which will encircle the tube 1, carrying the detonating material, and will thereby provide an inexpensive method of securing the lead in place. This outer tube is also waterproof and may be provided with an extra coat of varnish to insure this latter condition. In lieu of a complete tube I may provide tubular bands to secure the lead strips in place. In lieu of paper the tubes may be made of some suitable fabric which will disintegrate under the force of the explosion and the plugs for the ends of the tubes may be made of some suitable composition which will be ground to powder by the same force. In lieu of the strip of lead to engage the head of the rail, I may provide any suitable form of metallic wire or band to secure said torpedo in place. The strips of lead 4 are folded against the torpedo when it is arranged for packing and transportation, and this folding may be in the manner shown, or they may be folded in the opposite direction so that their ends will not project beyond the ends of the torpedo.

By making the torpedo-case of material readily destroyed, such as paper, sized fabric, and the like, all danger of injury resulting from flying portions of the usual metal torpedo is avoided.

Having thus described my invention, I claim and desire to secure by Letters Patent—

1. As a new article of manufacture, a non-metallic track-torpedo, having a filling of detonating material, means for securing said torpedo to the head of a rail, and means encircling the body of said torpedo for retaining said securing means thereto.

2. As a new article of manufacture, a track-torpedo comprising a casing of paper having a filling of detonating material exploding under pressure, means for securing said torpedo to the head of a rail, and means encircling the body of said torpedo for retaining said securing means thereto.

3. As a new article of manufacture, a track-torpedo of tubular shape, having a filling of

Claims 2 & 3 invalid on view of the sum act

detonating material exploding under pressure, means for securing it to the head of a rail, and means encircling the body of the torpedo for retaining said securing means thereto.

4. As a new article of manufacture, a track-torpedo comprising a tube of waterproof material, detonating material exploding under pressure disposed within said tube, securing means for the ends of the tube, means for holding the torpedo to the rail, and means encircling the body of the torpedo for retaining said securing means thereto.

5. As a new article of manufacture, a track-torpedo comprising a waterproof tube having detonating material within the same, plugs for preventing the escape of such detonating material, a secondary tube also of waterproof material encircling the main tube, and a strip 20 of material for securing the torpedo to the head of the rail confined by said secondary tube.

6. As a new article of manufacture, a track-torpedo consisting of a body of waterproof paper carrying a detonating substance exploding under pressure, means for confining said detonating material within the waterproof envelop, a secondary waterproof envelop inclosing the first, and a metallic strip 25 for securing the torpedo to the rail, said

strip being confined to the torpedo by the secondary envelop.

7. As a new article of manufacture, a track-torpedo consisting of a tube of waterproof paper carrying a detonating substance exploding under pressure, wooden plugs fitting the ends of said tube, a secondary paper tube 35 encircling the main tube, and a strip of lead for securing said torpedo to the rail, said lead being confined to the torpedo by the secondary tube.

8. As a new article of manufacture, a non-metallic track-torpedo having a filling of detonating material, metallic means for securing said torpedo to the head of a rail, and a 40 non-metallic means passing around the body of the torpedo and retaining said securing means thereto.

9. A non-metallic track-torpedo having a rail-engaging strap disposed on its under side, 45 and means completely encircling the body of the torpedo to retain the rail-engaging strap in place.

In testimony whereof I have signed my name to this specification in the presence of 50 two subscribing witnesses.

WILTON D. JACKSON.
